(Model.)

W. R. OSTRANDER.

Speaking Tube Mouth Piece and Bell Lever.
No. 235,285.

Patented Dec. 7, 1880.

ATTORNEYS.

UNITED STATES PATENT OFFICE

WILLIAM R. OSTRANDER, OF NEW YORK, N. Y.

SPEAKING-TUBE MOUTH-PIECE AND BELL-LEVER.

SPECIFICATION forming part of Letters Patent No. 235,285, dated December 7, 1880.

Application filed October 16, 1880. (Model.)

To all whom it may concern:

Be it known that I, WILLIAM R. OSTRANDER, of the city, county, and State of New York, have invented a new and Improved Speaking-Tube Mouth-Piece and Bell-Lever; and I do hereby declare that the following is a full, clear, and exact description of the same.

The speaking-tubes and levers for operating bell-wires in dwellings have been heretofore arranged as parts of distinct or separate apparatus. It is the object of my invention to combine them in one, and thus effect an economy in construction of such apparatus, and also promote convenience of communication between different rooms or apartments. To these ends I arrange a bell-wire lever in connection with the mouth-piece of a speaking-tube, so that they form one device or parts of one apparatus.

I show and describe, in connection with such mouth-piece and bell-lever, a shifting rosette and an annular frame, for which I propose to make a separate application for Letters Patent.

The construction and combination of parts are as hereinafter set forth, reference being had to accompanying drawings, in which—

Figure 1 is a face view of the complete device or apparatus embodying my invention, a portion being broken out. Fig. 2 is a view of rear side of the same. Fig. 3 is a section on line *x* *x*, Fig. 1. Fig. 4 is a perspective view of the bell-lever detached. Figs. 5 and 6 are, respectively, a plan and cross-section of the frame to which all the other parts are (in practice) attached. Figs. 7 and 8 are, respectively, a plan or face view and a cross-section of the shiftable rosette.

The letter A indicates a speaking-tube that may be supposed to extend from one room or apartment to another, or others between which it is desired to establish vocal communication. Such tube is provided with a mouth-piece, B, which is attached to a short exteriorly-threaded section, *a*, of gas-pipe or other suitable wrought-iron tubing.

C is an annular frame that is secured by screws passing through holes *c* to a block or stud (not shown) in the partition of building-wall. The frame C has a base-piece, *b*, through which the tubular section *a* of the mouth-piece passes, as shown.

The annular portion *g* of the bell-lever D fits loosely into the circular space inclosed by the ring of frame C, and the sheet-metal rosette E rests on said frame, its pendent inner flange, *d*, being interposed between part *g* of the lever D and the frame.

The rosette E has a narrow segmental portion cut out, as shown at *e*, Fig. 7, thus exposing a corresponding portion of frame C. The upper shoulder of the cut-out portion of the rosette serves as a stop for the bell-lever. The screw *f* is inserted in such exposed part of frame C and prevents the rosette from moving to the left, Fig. 1, as the tension of the bell-spring tends to make it.

The rosette E may be shifted one-quarter round to adapt the bell-lever D to turn to the right or left. When the rosette is thus shifted the screw *f* is inserted on the opposite side of the frame C, and the bell wire or wires *h* are correspondingly shifted, and the frame C also turned so that its base part *b* will lie horizontally instead of vertically.

The mouth-piece B of the speaking-tube A is spun from sheet metal and soldered to the pipe or tubular section *a*. Its exterior flange holds the bell-lever D and rosette E in place on frame C, yet allows the requisite vibration of the former.

I thus combine in one device the mouth-piece of a speaking-tube and the lever of a bell or alarm, so that a servant or other person in the room where the bell is located may be signaled and vocally communicated with with the greatest convenience and dispatch.

The cost of the device and the labor, time, and expense of attaching it to the wall are likewise only about half as much as when the two parts are made and attached separately.

What I claim is—

As an article of manufacture, a mouth-piece for a speaking-tube and a bell-lever pivoted to or upon said mouth-piece, and adapted, substantially as shown and described, to be secured to the wall by the same attachment.

The above specification of my invention signed by me this 7th day of October, 1880.

WILLIAM R. OSTRANDER.
